US00D936502S

(12) **United States Design Patent** (10) **Patent No.:** **US D936,502 S**
(45) **Date of Patent:** **** Nov. 23, 2021**

(54) **BOX BEAM LEVEL**

(71) Applicant: **Johnson Level & Tool Mfg. Co., Inc.**,
Mequon, WI (US)

(72) Inventors: **Timothy J. Wojciechowski**, Hubertus,
WI (US); **David Mencel**, Menomonee
Falls, WI (US)

(73) Assignee: **Johnson Level & Tool Mfg. Co., Inc.**,
Mequon, WI (US)

(**) Term: **15 Years**

(21) Appl. No.: **29/706,804**

(22) Filed: **Sep. 24, 2019**

(51) LOC (13) Cl. **10-04**

(52) U.S. Cl. **USPC .....** **D10/69**

(57) **CLAIM**

The ornamental design of a box beam level, as shown and described.

DESCRIPTION

FIG. 1 is an isometric view of a box beam level incorporating our new design, wherein the portions illustrated in phantom form no part of the claimed design;

FIG. 2 is a first side elevation view thereof;

FIG. 3 is a second, opposite side elevation view thereof;

FIG. 4 is a first end elevation view thereof;

FIG. 5 is a second, opposite end elevation view thereof;

FIG. 6 is a top plan view thereof; and,

FIG. 7 is a bottom plan view thereof.

1 Claim, 6 Drawing Sheets
